UNITED STATES PATENT OFFICE

JAMES F. DORAN, OF DANBURY, CONNECTICUT

HAT-POUNCING MACHINE

Application filed March 25, 1924. Serial No. 701,651.

This invention relates to the manufacture of hats and more particularly to machines for pouncing or finishing hats.

One of the objects of the invention is to provide a machine of the above nature which is practical and efficient throughout and capable of meeting the requirements of practical use in a highly satisfactory manner. Another object is to provide a machine of the above nature capable of turning out a high grade of work in a rapid and thorough manner. Another object is to provide a machine of the above nature adapted to operate at all times dependably and accurately. Other objects are to provide such a machine capable of performing an even and uniform operation upon all portions of the hat surface regardless of the irregularities of such surface, and capable of operating with equally efficient and uniform results upon all sizes and shapes of hats. Another object is to provide a machine of the above nature which is simply operated and wherein the degree of manual attention required during operation is reduced to a minimum. Another object is to provide such a machine characterized by smoothness of operation and freedom from parts susceptible to wear and deterioration. Another object is to provide such a machine wherein the various parts are conveniently disposed for ready accessibility. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings in which are shown one or more of the various possible embodiments of the several features of this invention,

Figure 1 is a top plan view of the machine. Figure 2 is a section taken substantially along the line 2—2 of Figure 1 showing in larger detail parts of the tool carrying mechanism.

Figure 3 is a plan view of the parts shown

in Figure 2, partly in section and certain connected parts being added.

Figure 4 is a side elevation of the machine, certain parts being cut away to better disclose the structure. 55

Figure 5 is a plan view of a cam follower shown in Figure 4.

Figure 5^a is a side elevation of the cam follower shown in Figure 5, together with the cam with which it coacts. 60

Figure 6 is a detailed front elevation of certain parts shown in Figure 4 with co-acting parts which are omitted from Figure 4.

Figure 7 is a side elevation in enlarged detail viewed from the side of the machine opposite to that from which the machine is viewed in Figure 4 showing the main body portion of the machine partly in section. 65

Figure 8 is a sectional detail of certain parts shown in Figure 7.

Figure 9 is a section taken substantially along the line 9—9 of Figure 7.

Figure 10 is a transverse sectional detail through certain parts of Figure 9. 75

Figure 11 is a section taken substantially along the line 11—11 of Figure 7.

Figure 12 is a section taken substantially along the line 12—12 of Figure 7.

Figure 13 is a section taken substantially along the line 13—13 of Figure 7. 80

Figure 14 is a sectional view of the parts of the machine comprising the upper left-hand portion of Figure 1, showing parts of the tool carrying mechanism and mechanism for actuating and controlling the tool. 85

Figure 14^a is a detailed side elevation of certain parts shown in Figure 14.

Figure 15 is a section taken substantially along the line 15—15 of Figure 14 certain parts not shown in Figure 14 being added and certain adjustable parts being shown in different relative positions to bring out the construction. 90

Figure 16 is a side view of the pouncing tool and associated mechanisms.

Figure 17 is a section taken substantially along the line 17—17 of Figure 16, and

Figure 18 is a section taken substantially along the line 18—18 of Figure 17 with the 100

addition of associated parts not shown in Figure 17.

Similar reference characters refer to similar parts throughout the several views of the drawings.

Referring now to Figures 1 and 4 of the drawings, the base portion of the frame of the machine comprises a bed or table 20 supported upon suitable legs 21. A pair of upright frame members 22 and 23 extend upwardly from the table or bed 20 and between the upper portions of these frame members 22 and 23 is a lateral hollow casing 24 provided with an upper stiffening web 25. The machine is driven either by motor or factory drive through a pulley 26 which is fast upon a shaft 27 at the rear of the machine. Upon this shaft 27 is a second pulley 28 from which is driven a pulley 29 through a belt 30. The upper portion of the upright frame member 23 comprises a gear box 31 containing gearing to be later described, through which the pulley 29 drives a shaft 32, shown in Figure 7, extending through the casing 24 to the front of the machine. The upper portion of the upright frame member 22 carries a casing 33 wherein the forward end of the shaft 32 is connected to drive certain mechanism, to be later described. The hat to be operated upon is supported upon a block 34, shown in Figure 1, which is supported by mounting means projecting from the front of the casing 33 and driven from the mechanism contained therein, as will all be more fully described hereinafter.

As shown in Figure 4, the shaft 32 adjacent its central portion carries a worm 35 which projects through the bottom of the hollow frame member 24. Adapted to be driven from this worm 35 is a worm wheel 36 fixed upon a transverse shaft 37. A part 38 of the casing 24 extends downwardly about the worm wheel 36. As shown in Figure 1, the shaft 37 carrying the worm wheel 36 has bearings in a pair of arms 39 and 40 which are pivoted upon a shaft 41 carried in a lug 42 upon the upright frame member 23, these latter parts being shown in Figure 4. By means of this mounting of the shaft 37 in the pivoted arms 39 and 40 the worm wheel 36 is capable of swinging downwardly out of engagement with the worm 35 to break the driving connection between the shaft 32 and the transverse shaft 37.

Turning again to Figure 1, securely fastened upon the two ends of the shaft 37 are a pair of cranks 43 and 44, one of which is counterbalanced as shown at 44^a for a purpose which will be later pointed out. Pivotally and adjustably connected to these cranks 43 and 44, as by bolts 45 and 46 and a plurality of coacting holes are a pair of connecting arms 47 and 48 respectively, extending toward the front of the machine.

Projecting laterally from either side of the forward casing 33 are a pair of supporting arms 49 and 50 which terminate in forwardly extending portions 51 and 52 respectively.

A T-shaped lever 53 shown more clearly in Figure 4 has a bearing upon the forward portion of the arm 52, and the forward end of the connecting lever 48 is pivoted to this T-shaped lever 53 as at 54. As brought out in Figures 2 and 3, a second T-shaped lever 55 has a bearing in the forward end of the frame arm 51, and the connecting lever 47 is pivotally connected to this T-lever 55 as at 56. The third arm of the T-lever 55, as shown in Figure 3, is adjustably clamped to a transverse tubular member 57 as by set-screws 58. The third arm of the T-lever 53 is also adjustably clamped to the tubular member 57 adjacent its other end, as best shown in Figure 14, by screws 59.

A rotation of the worm wheel shaft 37 therefore through the cranks 43 and 44 and the connecting levers 47 and 48, swings the T-levers 53 and 55 about their bearings in the frame arms 51 and 52 and this movement of the T-levers swings the tubular member 57. The bearings for the T-levers in the arms 51 and 52 are substantially in line with each other and they are also substantially in line with the hat block 34 so that the swinging movement of the tubular member 57 is substantially about a lateral axis through the block supporting the hat. Loosely mounted upon the tubular member 57 are a pair of arms 60 and 61 (the arm 61 being clearly shown in Figures 2 and 3), the other ends of which are adjustably clamped about the tubular member 62. This tubular member 62, through brackets 63 and 64 clamped thereabout, carries the pouncing tool which operates upon the hat supported upon the block 34. The pouncing tool is indicated generally by the numeral 65 in Figures 1 to 4 inclusive and its mounting and operation will be later described in detail. The pouncing tool bears against the surface of the hat and, as will be seen, is adapted to traverse from the position shown in Figure 1 upwardly and over the side of the hat and back again, as the T-levers 53 and 55 are swung by the action of the cranks 43 and 44 and the connecting arms 47 and 48 during rotation of the worm wheel shaft 37.

Turning now to Figure 7, there is shown the shaft 32 driven from gearing within the casing 31, as will be described, and extending through the tubular casing 24 into the forward casing 33 in front of which the hat is supported and rotated as has been mentioned. Securely mounted within the casing 33 and against the rear wall thereof is a plate member 66, shown more clearly in Figure 12, which comprises a pair of vertical V-ways 67. Slidably mounted in these vertical V-ways is a plate member 68 the face of which

is provided with a circular cam groove 69. The shaft 32 passes through an elongated opening 70 in the plate 68 and securely mounted on the end thereof, as by a pin 71^b, is a circular member 71, shown more clearly in Figure 11, which is provided on its front surface with a pair of transverse V-ways 72. The circular member 71 with its V-ways therefor rotates with the shaft 32. Carried in the V-ways 72 of the member 71 is a plate member or slide 73. Secured in the plate member 73 is a stud pin 74 which extends rearwardly through the elongated slot 75 in the member 71 and carries a segmental shoe 76 resting in the circular cam groove 69 of the cam plate 68. In the position shown in the drawing the parts within the casing 33 are all on center with respect to the axis of the shaft 32. It will be seen that by moving the cam plate 68 in its vertical stationary V-ways, the shoe 76 being engaged with the cam groove 69, the slide or plate 73 may be moved off center or into eccentric position with respect to the axis of the shaft 32.

This plate 73 has a forwardly projecting hub 73^a which, as better shown in Figure 9, is slotted to receive gripping fingers 79, shown as three in number, which are pivoted as at 80 within the hub. These gripping fingers 79 project outwardly through openings in a plate 81 secured to the forward end of the hub 73^a as by screws 82. The outer surface of the hub 73^a is threaded, and threaded thereon is a sleeve 83 which, when threaded outwardly, engages tapered surfaces of the fingers 79 as shown in Figure 7, urging them toward the axis of a projecting stud 78 to firmly grip the hub 34^a of the hat block. The fingers 79 are urged in the opposite direction by springs 84 so that when the sleeve 83 is threaded inwardly the grip upon the hat block is released. The stud 78 is adapted to enter the center hole in the hat block and center the hat block with respect to the plate 73. It is held in position between the plate 81 and the plate 73, and the rear hollow end thereof fits over the head of a bolt 77 which is centrally mounted on the plate 73 and secures the springs 84.

The outer end of the sleeve 83 is provided with a flange 85 and on the inner surface of this flange are a plurality of lugs 86 shown as four in number in Figure 9. A ring member 87 is spaced from the flange 85 by these lugs 86 and with the flange 85 forms a channel on the outer surface of the sleeve 83, which channel is subdivided by the projecting lugs 86. Upon the circular surfaces provided by the outer edges of the flange 85 and the ring 87 is slidably fitted a ring-shaped member 88 which has a pair of lugs 89 resting in the channel and adapted to slide with the ring 88 between the two lugs 86 between which they rest. The ring-shaped member 88 is provided with handles

90 by means of which it may be conveniently rotated.

By this construction just described a loose connection is had between the ring 88, carrying the handles 90, and the sleeve 83, a relative rotation of these parts being permitted to the extent allowed by the engagement of the lugs 89 with the lugs 86. This relative movement is of distinct advantage in threading the sleeve 83 inwardly along the hub 73^a to release the grip of the fingers 79 upon the hat block. When the block is gripped the gripping fingers are jammed tightly into engagement with the same and when it is necessary to remove the block considerable force must be applied to turn the sleeve 83 and release the grip. The loose mounting of the handle carrying member upon the threaded sleeve permits the former to be rotated back and forth relative to the sleeve to bring about a sharp impact of the lugs 89 against the lugs 86 and this impact readily loosens the gripping sleeve without necessitating great effort on the part of the operator. It will be evident that this is also of advantage in securing a firm grip upon the hat block as well as in bringing about the release of the same.

In order that the handle carrying ring 88 may not be wholly free to slide around relative to the sleeve 83, restraining means, such as that shown in Figure 10, is preferably employed. Each of the lugs 89 upon the ring 88 is recessed as indicated at 91 and fitted in these recesses are friction members 92 urged against the ring 88 by springs 93. This friction is preferably just enough to prevent sliding of the handle carrying ring 88 due to its own inertia but is not sufficient to interfere with manual operation thereof as above described. In the spaces 88^a between lugs 86 are positioned felt strips moistened with oil.

As best shown in Figure 11, about the periphery of the circular plate 71, which as above described, is rigidly secured to the shaft 32 and rotates therewith, is a brake band 94 adapted to be operated by a handle 95 which projects upwardly through the casing 33 and is pivoted thereto at 96. The brake band 94 is adapted to grip the rotatable plate 71 and thus hold the shaft 32 stationary while the gripping mechanism above described is being operated to grip or release the hat block. In Figure 11 the brake 94 is shown in gripping engagement with the plate 71 and it will be seen to be locked in such position by a toggle mechanism comprising a lever 97 connected to the handle 95 as at 98 and a lever 99 pivoted to the casing 33 as at 100. By pushing the end of the lever 99 downwardly toward the casing 33, the locking toggle is released and the brake is thereby released. The brake is adjusted by means of lock nuts 101 upon a

threaded pin 102 between the handle 95 and the opposite end of the brake band 94. It may be here noted that this brake is preferably employed but may be dispensed with if desired, the inertia of the shaft 32 and its parts serving ordinarily to hold the shaft stationary as the hat block gripping mechanism is operated by the impact mechanism described.

The mechanism within the casing 33 is adapted to operate in oil which is placed in the bottom portion of the casing and picked up by the revolving plate 71. The oil may be introduced through a cap 103 at the top 10 of the casing, and a drain 104 is provided at the bottom for drawing off the oil when desired. In order that this oil may be prevented from working out of the casing 33 toward the block supporting the hat, a ring 15 shaped wiper 105 is seated in the forward wall of the casing and urged against the surface of the rotating plate 73 by spring pressure. A plate member 106 rests loosely about the sleeve 83 and is spring pressed and held against the outer surface of the casing 33 as by bolt 107 passing through slot 20 106^a, to prevent the access of dirt or dust to the interior of the casing.

As has been described above, the pouncing tool, thus far generally designated by the numeral 65, is adapted to traverse across the surface of the hat supported upon the rotating hat block 34, from the tip of the hat upwardly across the square of the hat to the side portions thereof, the square being the term generally applied to the portions of the hat joining the tip and the sides. When the pouncing tool is operated upon the side portions of the hat, its pressure against the hat is determined by the weight of the pouncing tool and its connected parts, restrained or augmented to a predetermined degree by means which will be later described. The hat is oval in shape, that is it has two axes, a major axis between its front and rear ends and a minor axis at right angles thereto. Thus if the hat is continually rotated about its axis through the tip, the side surfaces thereof in contact with the pouncing tool generate an oval. The result is that when the tool is operating upon the side portions of the hat, during part of the rotation of the hat, a lifting effect is imparted to the tool which increases the pressure of the pouncing tool against the hat, whereas, during another part of the rotation, the pouncing tool is permitted to fall and the pressure of the pouncing tool against the hat is decreased. The result of this is uneven finishing, the portions of the hat which do the lifting being operated upon by the pouncing tool to a greater degree than the portions of the hat operated upon while the pouncing tool is falling. Turning again to Figure 7, it will be seen that by proper movement up

and down of the non-revolving slide 68 in its V-ways, the axis of the stud 78 which is coincident with the axis of the hat through the tip may be shifted during rotation of the hat. This shifting may be made such by proper movement of the slide 68 that the side surfaces of the hat in contact with the tool travel not in an oval, but in a circle.

It may be here noted that in order to properly position the hat block carrying the hat with its major axis in proper relation to the V-ways of the rotating plate 71, a pin 108 is positioned in the front plate 81 against which the base of the hat block rests. This pin is adapted to engage with a recess in the hat block on the line of its minor axis.

The position of the slide plate 68 in its V-ways is controlled by a lifting rod 109 passing upwardly through the bottom of the casing 33. Suitable packing 110 held in place by a bushing 111 is provided about the rod 109 to prevent oil from leaking downwardly along the rod from within the casing 33.

The lifting rod 109 passes downwardly through the table 20 of the frame of the machine and, as shown in Figure 4, at its lower end is connected as at 112 with a foot lever 113 pivoted to the frame leg 21 as at 114. Thus a downward pressure upon the foot lever 113 will lift the rod 109 and raise the slide or cam plate 68 in its V-ways. As shown in Figure 7, the rod 109 above the table 20 is threaded and threaded thereon are two pairs of lock nuts 115 and 116 respectively. The lock nuts 115 are set on the rod so that they rest upon the frame 20 when the cam slide 68 is in central position concentric with the shaft 32. Between the lower face of the frame 20 and a clamping collar 117 is a compression spring 118 which urges the rod 109 downwardly tending to maintain the lock nuts 115 against the upper surface of the frame and the cam plate 68 in central position.

Between the two sets of clamping nuts 115 and 116 is a collar 119 fitted loosely about the rod 109. Threaded upon this collar 119 is a collar 120 which, as best shown in Figures 4 and 6, has a right angle stud 121 upon which is pivoted a link 122. The other end of the link 122 is pivoted upon a stud pin 123 which passes through the end portion of a rock lever 124 and is secured therein as by a set screw 125. This rock lever 124 is pivoted upon a pin 126 secured in a lug 127 of the upright frame arm 22.

About the worm wheel shaft 37 is a cam 128 which is secured to the side of the worm wheel 36 and rotates therewith. This cam is adjustable about the axis of the shaft 37 by a slotted connection and pin 129 by which it is secured to the worm wheel. This cam 128 is adapted to engage a roller 130 mounted upon the right hand end of the rock lever 124, the details of which mounting are shown in Figure 5.

When the worm wheel 36 is in engagement with the worm 35 and is revolved thereby the cam 128 is revolved and, contacting the roller 130, the cam pushes the right hand end of the lever 124 downwardly raising its left hand end, which through the collar 120 engaging the upper lock nuts 116, raises the lift rod 109 and the cam plate 68. The cam 128 thus serves to bring about the desired eccentricity of movement of the hat to cause its side surfaces contacting with the pouncing tool to move in a circle. The degree of oval of a hat varies through different sections from the brim to the tip so that as the pouncing tool traverses the hat a changing degree of eccentricity is required. The outline of the cam 128 is designed to give the proper change in the degree of eccentricity of the cam plate 68 so as to be in harmony with the outline of the oval section with which the traversing pouncing tool is in contact at any instant. This change is slightly different on the sections of different styles of hats and the cam is made with a broad face, the shape of which at one side is suitable to take care of one extreme of style, and the shape of which at the other side is suitable to take care of the other extreme of style. The intermediate portions of the surface of the cam take care of styles which are between these two extremes.

The roller 130 has an adjustable mounting upon the rock lever 124 so that its position may be adjusted from one side of the cam 128 to the other to contact different portions thereof according to the style of hat being operated upon. As shown in Figure 5, the roller is loosely mounted upon a nut 131 which is threaded upon a pin 132 transversely mounted in the rock lever 124. A projection 133 holds the nut 131 from rotation and by turning the pin 132 by means of the knurled handle 134 the nut and roller are moved along the pin.

Referring again to Figures 7 and 12, it will be seen that when the cam plate 68 is moved upwardly into eccentric position with respect to the shaft 32, and when the segmental slide 76 is in the upper position in the circular cam groove 69 (this position being shown in the drawings) the axis of the stud 78 and hence the axis of the hat are drawn upwardly an amount equal to the eccentricity of the cam plate 68. When a half revolution occurs, the segmental slide 76 moves to the bottom position in the circular cam groove 69 and again moves the axis of the stud 78 upwardly the same distance. Therefore, this eccentric motion occurs twice in a revolution and therefore there is generated by the axis of the stud 78 an oval whose major axis is greater than its minor axis by twice the distance that the cam plate 68 has been moved upward off center. To set the machine so that an oval of the hat to be operated upon may be generated, the machine is stopped when the cam 128 has revolved so that its

highest point is contacting the roller 130. Thereupon the rod 109 is moved up by means of the foot lever 113 and a member of a thickness equal to half the difference between the major and minor axes of the oval required is placed beneath the lock nuts 115. The lock nuts 115 are allowed to rest upon this member and thereupon the lock nuts 116 are moved against the upper surface of the collar 120 and locked securely in place. The member is then removed from beneath the lock nuts 115 and the machine is set to generate an oval of the required size.

The spring 118 in addition to tending to keep the cam plate 68 on center and to steady its movement, also tends through contact of the collar 120 with the lock nuts 116 to force the left-hand end of the rock lever 124 downwardly and the right-hand end thereof upwardly. The spring 118 therefore, through the lever 124, tends to raise the cam 128 together with the shaft 37 and the worm wheel 36 tending thus to force the worm wheel into engagement with the worm.

The worm wheel shaft 37, as has been described, is mounted in a pair of pivoted arms 39 and 40 whereby the worm wheel 36 may swing into and out of engagement with the worm 35. One of these pivoted supporting arms 40 is shown in Figure 7 pivoted upon the shaft 41. This arm 40 has an extension 135 through which passes a rod 136 suspended from a web of the upper frame member 24. About this rod 136 and between the arm 135 and a nut 137, is placed a compression spring 138. The weight of the supporting arms 39 and 40 together with the parts carried thereby, including the shaft 37 and the worm wheel 36, tends to swing the worm wheel downwardly out of engagement with the worm 35. By regulation of the adjusting nut 137 the compression in the spring 138 may be adjusted and this compression is so adjusted that it will just nearly balance the downward pressure caused by the weight of the arms 39 and 40 and the parts which they carry. The spring 118 therefore upon the rod 109 acting through the rock lever 124 easily raises the worm wheel into engagement with the worm as the cam 128 revolves against the roller 130 to actuate the eccentric mechanism. The roller, as has been described, then acts temporarily as a fixed abutment against which the cam 128 revolves, the worm wheel being thereby raised into engagement with the worm before the subsequently acting surface of the cam moves the roller and the rock lever 124 downwardly to actuate the eccentric mechanism.

Normally to start the operation of the machine upon a hat, as described with regard to Figure 1, the tubular members 57 and 62 are swung about the bearings on the end portions of the arms 51 and 52 to bring the tool 65 to the position shown in the drawing,

against the tip of the hat. At this time the worm wheel 36 is out of mesh with the worm 35. The tubular member 57, as has been described, is connected through T-levers 55 and 53, connecting arms 47 and 48 and cranks 43 and 44 with the worm wheel shaft 37. When the tool 65 is swung by hand to starting position against the tip of the hat therefore the worm wheel shaft 37 is rotated. The cam 128 adjustably fastened to the side of the worm wheel 36 is set so that this rotation by hand to bring the tool to starting position against the tip of the hat brings the beginning of the acting portion of the cam in contact with the roller 130. Thus the machine is automatically started by simply swinging the pouncing tool by hand into operative position against the tip of the hat. The counterweight 44^a upon the crank 44 facilitates this action and prevents backward movement.

As shown in Figure 7, there are provided beneath the worm shaft 37 a pair of props 139, one only of which is shown in this figure, the other being similar in construction and positioned on the opposite side of the worm wheel. These props 139 are fastened upon a shaft 140 which is pivoted in a lug on the top of the frame table 20. The props are provided with an adjustable counterweight 141 which causes them to swing with their shaft 140 to the position shown in the drawing immediately that the worm wheel 36 is raised upwardly into engagement with the worm. In this position the props support the worm wheel shaft 37 and its parts assisting the action of the cam 128 in holding the worm wheel in engagement with the worm, as has been described above. The weight carried by the props 139 is slight, their purpose being chiefly to take care of the extra downward pressure caused by the worm drive and they are an assurance against disengagement of the worm wheel and worm or the stopping of the machine until it is desired.

Secured upon the shaft 140 with the props 139 is a tripping lever 142. A clamping collar 143 adjustably secured upon the worm wheel shaft 37 carries a swivel mounted trip 50 144 which is adapted to engage the tripping lever 142 at a predetermined point in the rotation of the shaft 37 to automatically throw the props 139 out of supporting position. The point at which this tripping of the props 139 occurs may be varied through adjustment of the clamp 143 and the clamp is normally set so that this action takes place just after the pouncing tool 65 has traversed over the side portions of the hat and back 60 to the tip.

Referring to Figure 5^a, the first action portion of the cam 128 which, as above described, acts to automatically lift the worm wheel 36 into engagement with the worm 35 when the 65 pouncing tool 65 is placed in starting posi-

tion on the tip of the hat, is designated by the reference character 128^a. The last acting portion which is effective when the pouncing tool has traversed across the side portions of the hat and back to the tip, is the portion at 128^b. Between these two portions 128^a and 128^b the surface of the cam is undercut substantially at 128^c. This undercut portion 128^c revolves past the surface of the roller 130 just after the tool 65 reaches the tip of the hat at the end of its traversing movement. The adjustment of the lock nuts 115 on the lifting rod 109 is such that when the first acting portion 128^a of the cam is in engagement with the roller 130 the cam does not act to lift the rod 109, the sliding cam plate 68 being on center, (no eccentric motion being desired at this point when the tool is operating upon the tip of the hat). The lock nuts 115 being at this point in engagement with the surface of the table 20, this position of the roller 130 in engagement with the part 128^a of the cam marks the uppermost position which the roller can assume under the action of the spring 118 on the lifting rod 109. The roller 130 therefore does not contact with the undercut portion 128^c of the cam, but leaves a clearance between this undercut portion and the roller surface. At this point the pouncing tool 65 has completed its traverse and returned to the tip of the hat and the cam 144 trips the props 139 and the worm wheel is allowed to drop downwardly out of engagement with the worm. As soon as this happens the counterweight 44^a of the crank 44 rotates the shaft 37 a little further and the pouncing tool 65, by means to be later described, is drawn out of engagement with the hat.

From the above it will be seen that the machine thus far described is automatically started by swinging the pouncing tool 65 into engagement with the tip of the hat. Furthermore, the operation is automatically stopped when the tool has traversed across the surface of the hat and back to the tip.

It is desirable that the roller 130 move a short distance up into the undercut portion 128^c of the cam 128 so that it is in position to automatically raise the cam and its parts upwardly as soon as the first acting portion 128^a of the cam comes into contact with the roller. As has been described above, the spring 118 on the lifting rod 109 does not do this. For this purpose, as shown in Figure 6, there is attached to the pin 123 at the left-hand end of the rocker arm 124 a rod 145 extending downwardly through the table 20 and provided therebeneath with a compression spring 146 and adjusting nut 147. An adjustable collar 148 on the rod 145 above the table 20 determines the extent to which the spring 146 may raise the roller 130 and this is adjusted so that the roller slightly enters the undercut cam portion 128^c, leaving

the clearance required to permit the worm wheel to drop out of engagement with the worm at this point.

Referring to Figure 4, by pressing downwardly upon the foot lever 113 the roller 130 may at any time be forced downwardly out of engagement with the cam 128. Threaded into a lug 149 at the right-hand end of the lever 124 carrying the roller 130 is an adjustable stud 150 and secured to the shaft 140 which carries the props 139 is a pin 151. When the foot lever 113 is depressed carrying the cam roller 130 downwardly the stud 150 strikes the pin 151 and swings the props 139 out of supporting position. Thereupon the pressure of the roller 130 upon the cam 128 having thus been relieved and the props 139 thrown out of supporting position, the worm wheel 36 drops out of mesh with the worm 35.

The operation of the machine may therefore be stopped at any time by operation of the foot lever 113. Furthermore, by the use of this foot lever the pouncing tool 65 may be swung to any position of its traverse that is desired. Whereupon, the pressure upon the foot lever being relieved, the pouncing tool will automatically resume its traverse and the machine will automatically stop when the traversing movement is completed and the pouncing tool returns to the tip of the hat. In this manner any desired portion of the hat may be operated upon to any desired degree independently of the remaining portion of the hat.

Referring now again to Figure 7, there is shown the pulley 29, which, as has been mentioned, through gearing within the rear casing 31 drives the shaft 32. The hub 29^a of the pulley 29 is secured to a hollow shaft 152 which rotates freely within an extension 153 of the back cover plate 31^a of the casing 31. The right-hand end of this hollow shaft 152 forms a pinion 154 which meshes with a gear 155 freely mounted upon a stud bearing 156. The size relation of the gears 155 and 154 is 2 to 1. The stud bearing 156 projects through a slot in the cover plate 31^a and is secured by a nut 157 to an arm 158 which is freely mounted to oscillate on the exterior of the extension 153 of the cover plate. These parts are also shown in Figure 13.

Projecting from the inner face of the gear 155 is a drive pin 159 which enters an opening in a link 160. Engaging another hole in the link 160 is a second drive pin 161 which projects from the face of a pinion 162. The pinion 162 is of the same size as the pinion 154, has its bearing on a fixed stud 163 and meshes with a gear 164 which is of the same size as the gear 155. This gear 164 is mounted to revolve freely on the rear portion of the shaft 32.

On the front face of the pinion 154 are

clutch dogs 165 and on the rear face of the gear 164 are clutch dogs 166. Between these two clutch faces is a spacer collar 167. The rear end of the shaft 32 is hollow and slidably fitted therein is a slide piece 168 circular in cross section and adapted to slide longitudinally within the hollow shaft 32. This slide piece 168 adjacent its front end has a transverse slot in which rests a double clutch dog 169 which is held in place by the pointed end of a rod 170 passing centrally through the slide piece 168 from its rear end. The clutch dog 169 projects through an elongated transverse slot 171 in the hollow portion of the shaft 32. The clutch dog 169 is therefore in continual driving engagement with the shaft 32.

By means of the slide piece 168, the clutch dog 169 may be moved backward to engage with the dogs 165 on the pinion 154, or forward to engage with the dogs 166 on the gear 164. The pinion 154 is in continual driving relation with the gear 164 through the gears 155 and 162 and the link 160, but without the clutch dog 169 there is no driving connection between the gear 154 and the shaft 32, since the gear 164 is loosely mounted upon the shaft 32. In the position shown in the drawing, the clutch dog 169 is in engagement with neither the gear 154 nor the gear 168 and no drive is imparted to the shaft 32. When the clutch dog 169 is moved backward by the slide piece 168 it engages the dogs 165 and a direct drive is had from the pinion 154 to the shaft 32. When the dog 169 is moved forward by the slide 168 it engages the dogs 166 and a driving connection is established from the pinion 154 through the gear 155, link 160, pinion 162 and gear 164 to the shaft 32, driving the latter at $\frac{1}{4}$ the speed of pinion 154.

The position of the slide 168, and hence of the clutch dog 169 is controlled by a lever 172 through which the slide 168 passes as at 173 and is loosely held by a clamp nut 174. The lower end of the lever 172 is pivoted at 175 to a fixed support 176 threaded into a bracket 177 which is secured to the upright frame member 23. The upper end of the lever 172 is pivoted at 178 to the end of a rod 179 which extends forwardly through two bearing supports 180 and 181 to the front of the machine. About this rod 179 adjacent its central portion is a slidable collar 182 between which, and a pair of clamping collars 183 and 184 are interposed compression springs 185 and 186. As shown in Figures 1 and 4 the slidable collar 182 has pivoted thereto at 187 a rod 188, which at its other end is pivoted to a handle 189. This handle 189 is pivoted upon a pin 190 in the web 25 of the frame and is adapted to swing about the pin 190 to move the rod 188 backward or forward longitudinally of the machine.

A backward movement of the handle 189

130

acting through the springs 185 and 186 yieldingly urges the rod 179 rearwardly and hence yieldingly urges the clutch dog 169 into engagement with the dogs 165 on the gear 154. A forward movement of the handle 189 in like manner yieldingly urges the clutch dog 169 into engagement with the dogs 166 on the gear 164. By means of the handle 189 therefore, the clutch dog 169 may be moved in either direction from its neutral position shown in the drawing, and this through a yielding connection which greatly decreases wear and tear upon the clutch parts. In the web 25 are provided three holes 191 which are adapted to be engaged by a pin 192 carried by the handle 189. This pin is yieldingly urged into engagement with the holes 191 and is controlled by suitable retracting device 193 projecting from the top of the handle. These three holes correctly position the handle 189 for positioning the clutch dog 169 in its three respective operating positions.

The rod 179 extending forwardly through its forward bearing support 181 is provided adjacent its end with a pair of collars 194 and 195. The space between these collars is in line with, and adapted to receive the shank of the brake handle 95 when the brake is in gripping engagement with the plate 71 upon which it acts, and when the handle 189 is positioned in the central hole 191 and the clutch dog 169 is therefore in neutral position. Thus the rod 179 cannot be moved and the rotation of the shaft 32 cannot be started until the brake handle 95 is moved to position of release. Furthermore, when the clutch dog 169 is in either of its driving positions to drive the shaft 32, one of the collars 194 or 195 is in the line of movement of the brake handle 95 so that the brake cannot be applied while the shaft 32 is being driven.

Turning again to the gearing contained in the casing 31, shown in Figure 7, the axis 45 of the movable stud bearing 156 carrying the gear 155 is shown in line with the fixed stud 163 carrying the gear 162. With these parts in such position a constant motion is transmitted from the constantly rotating gear 155 through the link 160 and its drive pins 159 and 161 to the gear 162. The axis of the stud 156 may be thrown out of line with the axis of the stud 163 by swinging the stud supporting plate 158 about its bearing 50 on the extension 153 of the back cover plate 31^a. The action between the gears 155 and 162 through the link 160 and its driving pins, is that of a four-bar linkage. When the stud 156 is positioned out of line with the 60 stud 163 a variable angular velocity is imparted to the gear 162 and this variable angular velocity is transmitted through the gear 164 and clutch dog 169 to the shaft 32. The greater the distance between the axis of the driving gear 155 and the axis of the driven

gear 162, the greater the variation in angular velocity during each revolution. Due to the ratio of 1 to 2 between the gears 162 and 164, this change in angular velocity of the shaft 32 occurs twice in each revolution of the shaft 32. The hat rotated by the shaft 32 may thus be given a rotation of varying angular velocity, which velocity changes twice during each rotation of the hat.

On account of the oval shape of the hat, it is evident that the end portions of the sides of the hat are of sharper curvature than the broader and flatter side portions, and therefore the contacting surface of the pouncing tool on these end portions is less than the contacting surface of the pouncing tool on the flatter side portions. The result of this is that the intensity of pressure of the pouncing tool on the ends of the hat crown is greater than the intensity of pressure of the pouncing tool on the side portions thereof, causing uneven finishing of the hat unless compensated for. By the mechanism just described, the hat may be made to rotate faster when the pouncing tool is operating upon the end portions, than when the pouncing tool is operating upon the flatter side portions.

In order that the changing angular velocity may be in harmony with the rotation of the hat, so that the greatest angular velocity will be thrown into action when the pouncing tool is working on the end portions of the hat crown and so that the slowest angular velocity will be acting when the pouncing tool is working on the flatter sides of the crown, the axis of the hat must be set in definite angular relation with respect to the angular velocity mechanism within the casing 31. This is done by placing the elongated transverse slot 171 in which the dog 169 slides in line with the transverse V-ways of the revolving plate 71. As has been described before the pin 108 on the front plate 81 aligns the major axis of the hat with these V-ways. In order to set the angular velocity changing mechanism in proper position so that the resultant fast and slow motions of the shaft 32 will occur at the proper time in reference to the major axis of the hat, and in harmony with the oval changing mechanism, the position of the pin 161 is set in predetermined relation to the line of the dogs 166 on the gear 164 and by changing the position in which the two gears 162 and 164 mesh, the angular change may be caused to occur earlier or later in reference to the shaft 32 and the major axis of the hat.

As has been stated in connection with the description of the oval changing mechanism, the oval sections of the hat vary from the brim toward the tip of the crown portion, this change varying with different styles of hats. By the mechanism now about to be described, the degree of variation in the angular velocity of the hat is automatically

rying rod 226 is an adjustable clamping collar 230 above the bracket 228 and by proper adjustment of this clamping collar the effect of the weights 227 may automatically be removed at any desired point in the traverse of the pouncing tool. For example, the collar 230 may be adjusted so that the action of the weights is removed just as the pouncing tool passes over the square of the hat and with this adjustment the pouncing tool continues its traverse across the sides of the hat and back again to the square exerting the pressure occasioned only by its own weight. Thereupon when the pouncing tool traverses back across the top of the hat, the weights 227 again come into action to draw the pouncing tool against the hat.

Above and below the bracket 228, upon the rod 225, are a pair of brackets 231 and 232 respectively which carry a vertical rod 233 passing through an opening in the bracket 228. This rod 233 keeps the weight carrying rod 226 in line with the pulley 223 and prevents its swinging into contact with the side of the machine.

Turning again to Figure 1, the shaft 27 carrying the pulleys 26 and 28 at the rear of the machine, enters the gear box 234 in which it is connected through suitable gearing to drive a shaft 235 projecting from the gear box 234 at right angles to the shaft 27. This shaft 235 carries a pulley 236 which, through a belt 237, drives a pulley 238. The belt 237 is provided with an idler tension pulley 239 mounted upon a bracket 240 which is pivoted upon the supporting arm 52.

Referring to Figure 14, there is shown a pulley 238, formed integrally with which is a sleeve 241 which passes through the tubular end portion 52^a of the supporting arm 52. The pulley 238 and its sleeve 241 are therefore rotated within the tubular part 52^a and at high speed by the belt 237 from the gearing within the gear box 234. The sleeve and pulley rotate preferably upon ball bearings 242 and 243. The outer race of the ball bearing 243, as will be seen, is supported within the hollow hub of the T-lever 53 which has been described.

Within the pulley 238 is secured a transverse stud pin 244 upon which is freely mounted a rock shaft 245. The outer end 245^a of the rock shaft 245 through ball bearings 246 and 247 carries an oscillating arm 248. The inner end 245^b of the rock lever 245 projects freely within the driven sleeve 241. Its upper surface 245^c is shaped to conform to the inner wall of the sleeve 241 so that when, as shown in the drawing, this surface is against the inner wall of the sleeve 241, the axis of the outer end portion 245^a is in line with the axis of the pulley 238 and the sleeve 241. Thus, when the surface 245^c moves away from the wall of the sleeve 241 by the lever 245 rocking upon its pin 244, the outer end 245^a is

moved out of alignment with the axis of the sleeve 241 so that its rotation generates a cone and imparts an oscillating movement to the arm 248. The surface 245^d opposite the surface 245^c also conforms to the contour of the inner wall of the sleeve 241 and when this surface 245^d contacts the wall of the sleeve 241 the axis of the outer end of the arm 245^a is thrown off at its greatest angle from alignment with the axis of the sleeve 241, and in this position the oscillations imparted to the arm 248 are of maximum amplitude. Between these two positions of the arm 245^b, that is, between its position with the surface 245^c in contact with the sleeve wall and its surface 245^d in contact with the sleeve wall, a varying amount of oscillation is imparted to the arm 248. The arm 248 is restrained from rotation with the arm 245^a by means of a light arm 249 which engages with a slot in a member 250 projecting from the left-hand end of the tubular pouncing tool carrying member 62. This member 250 is preferably of light material such as fibre and is secured by spring connection 251 passing through the tubular member 62 and connected to a cap 252 at the opposite end thereof as shown in Figure 3.

At the end of the oscillating arm 248 is a hollow pin 265 through which the arm 249 passes and to which is pivoted a lug 266. Pivoted to this lug 266 is a connecting rod 267 through which the oscillations of the arm 248 are imparted to the pouncing tool 65 which, as was earlier described, is mounted upon the tubular member 62 by means of adjustable bracket 64. The mounting of the pouncing pad to partake of these oscillations will be later described in detail.

The portion of the arm 245^b below an axial line, as viewed in Figure 14, is made heavier than the upper portion. Since the arm 245^b is free to swing on its bearing pin 244 the heavier lower side tends always by centrifugal force during rotation to swing the arm so that the surface 245^a tends to move toward the wall of the sleeve 241 and the opposite surface 245^c tends to move away from the wall of the sleeve. In order to aid this movement in case oil or grease should tend to stick the surface 245^c against the wall of the sleeve 241, a compression spring 253 is seated in the arm 245^b and through a slide 254 tends to urge the surface 245^c away from the sleeve wall. Centrifugal force therefore tends always to throw the rock lever 245 into position to impart oscillations of maximum amplitude to the arm 248.

Slidably mounted within the sleeve 241 and adapted to slide longitudinally therein, is a member 255 which is substantially circular in cross section and projects from the right-hand end of the sleeve 241. The inner end of the slide 255 is tapered and seated therein is a hardened shoe 256 which contacts with a

changed, during traverse of the pouncing tool across the hat, in harmony with these changing oval sections. The cam 128, as described, has an outline shaped to move the rock lever 124 (shown in Figure 4) through the roller 130 in accordance with the changes in the oval section which the pouncing tool is traversing. This movement of the rock lever 124, by the cam 128, is therefore utilized to affect the angular velocity mechanism to vary the degree of velocity change imparted to the rotating hat.

Referring now principally to Figures 7 and 13, on the back of the cover plate 31^a are vertical guides 196 in which rests a slide 197 having an angular slot 198 through which the stud 156 carrying the gear 155 passes. Thus, by movement of the slide 197 in its guides, the stud 156 may be swung to one side or the other relative to the fixed stud 163. Pivoted to the slide 197, at 199, is a rod 200, which as shown in Figure 4, is pivoted at its lower end at 201 to the right-hand end of a rock lever 202. This lever 202 is pivoted at 203 upon a bracket 204 and at its other end is pivoted at 205, a link 206. The rock lever 124 is provided with a plurality of holes 207 through which connection is made between the link 206 and the rock lever 124 by a pin 208.

Thus the swinging of the rock arm 124 in response to the action of the cam 128, is imparted to the vertical slide 197 which accordingly moves the axis of the stud 156 carrying the gear 155. In this manner the degree of velocity change in the rotation of the hat is automatically varied in accordance with the changing oval sections of the hat which the pouncing tool is traversing. The distance of the connection 208 between the link 206 and the rock lever 124 determines the amount of movement imparted to the vertical slide 197 by the cam 128. This may be adjusted by changing the connection 208 along the different holes 207.

Connected to the rock lever 202 at 209, is a rod 210 which passes downwardly through a lug 211 and is provided with a compression spring 212 and an adjusting nut 213. The spring 212 acts in opposition to the upward movement of the slide 197 and serves to steady its movement. As shown in Figure 13, a slot 214 is provided in the plate 197 engaging with a pin 215 in the cover plate 31^a to prevent accidental movement of the plate 197 too far, so as to throw the linkage controlled by the stud 156 out of proper position and cause binding.

During the changing angular velocity of the shaft 32, the mass of the shaft and its connected parts, including the hat, tend through their inertia, to continue at the faster angular velocity so that there is a tendency for the changes from the fast angular velocity to the slow angular velocity to be non-uniform.

Furthermore, there is some tendency toward an oscillating movement of the shaft 32 allowed by play in the gears due to the action of the pouncing tool upon the surface of the hat. In order to overcome these difficulties and others, as shown in Figures 7 and 8, there is placed against the shaft 32 a friction member 216 which is urged against the shaft by a compression spring 217 contained in a housing 218 secured to the frame 24. By means of the set screw 219 and lock nut 220, the compression in the spring 217 and hence the restraining action of the friction member 216 on the shaft, may be adjusted.

Turning now to Figure 15, there is shown the tubular member 57 which, as has been described, is swung by the action of the cranks 43 and 44 on the worm wheel shaft 37, through the connecting arms 47 and 48, to cause the pouncing tool 65 to traverse across the surface of the hat supported upon the block 34. As has also been described, the pouncing tool 65 is carried by the tubular member 62 which is connected to the swinging tubular member 57 by arms 60 and 61. Adjustably clamped upon the pouncing tool carrying tubular member 62 is an arm 221 which serves as an anchorage for the end of a cable 222. This cable 222 passes rearwardly over a pulley 223 mounted in a bracket 224 which is adjustably clamped on an upright vertical rod 225. This rod 225 is secured in the supporting arm 52 and passes downwardly therethrough toward the base of the machine. Secured at the lower end of the cable 222 is a rod 226 at the lower end of which are mounted removable weights 227. The weight carrying rod 226 passes through a bracket 228 which is slidably supported upon the vertical rod 225 and whose position thereon is adjustable by means of a clamping collar 229.

The tubular member 62 is thus drawn toward the hat and the pouncing tool is pressed into engagement with the surface of the hat by the action of the weights 227 pulling upon the arm 221. It will be seen that the pressure of the pouncing tool against the hat thus occasioned may be varied and regulated by adjusting the arm 221 about the tubular member 62 to vary the length of the arm of force through which the weights act, and also by the removal or addition of weights 227. The arm of force through which the weights act is lessened by adjusting the arm 221 toward the positions shown in dotted lines in Figure 15 and, by proper adjustment, the weights 227 may be made to either increase the pressure of the pouncing tool against the hat, or to exert a lifting effect upon the pouncing tool and decrease the pressure due to the normal weight of the pouncing tool and its parts. In this manner a wide range of adjustment of pressure of the pouncing tool against the hat surface is obtainable. About the weight car-

roller 257 mounted on a transverse pin at the right-hand end of the arm 245.

The slide 255 rotates with the sleeve 241 and the rocker arm 245, and on the right-hand end thereof are mounted a collar 258 and the inner race of a ball bearing 259, held in place by lock nuts 260. A compression spring 261 about the slide 255 tends to push the slide to the right, tending to draw the shoe 256 away from contact with the roller 257 and to allow the arm 245^b to swing about its pin 244 by centrifugal force, as described.

The outer race of the ball bearing 259 is held in a non-revolving collar 262 which is slidably held within a cap 263. An extension 264 of this collar 262 passes through an opening in the end of the cap 263. The spring 261 tends always to force the slide 255, the ball bearing 259 and the collar 262 to the right. In the position shown in the drawing, this movement is restrained, the spring 261 being compressed its greatest amount to hold the rock arm 245 co-axial with the sleeve 241 whereby no oscillation is imparted to the arm 248. It will be seen that by controlling the position of the collar 262 in the cap 263 through the extension 264, the amount to which the surface 245^c of the lever 245^b is thrown away from the wall of the sleeve 241 by centrifugal force may be controlled, and the amplitude of oscillation given to the arm 248 may thereby be controlled. The further the extension 264 is permitted to move to the right, under the urge of the spring 261, the greater will be the amplitude of oscillation imparted to the arm 248 and hence to the pouncing tool 65.

In the outer end of the extension 264 of the collar 262, is threaded a screw 268 in a slot in which is pinned a yoke 269 which may be seen by reference to Figures 1 and 4. The ends of this yoke 269 are swiveled at 270 to the end of the bell crank lever 271 which forks around the cap 263. The bell crank lever 271 is pivoted upon a pin 272 in a lug 273 forming a part of the T-lever 53 and has a hooked extension 275 which enters through a slot to the interior of the tubular member 57. Over this end 275 of the bell crank 271 is hooked the end of a pull rod 276 which passes through the tubular member 57 and is connected at its other end, as shown in Figure 3. Referring to this figure, the right-hand end of the pull rod 276 passes through a collar 277 which fits loosely within the end of the tubular member 57. Passing through the collar 277 is a pin 278 which engages with slots in the end of the tubular member 57 and prevents rotation of the collar. Freely mounted upon the outside of the tubular member 57 is a ring 279 which is fastened to a handwheel 280 and has a cam surface adapted, when the hand-wheel and ring are turned, to engage the pin 278 and thrust it, with the collar 277 and the rod 276, to the right. On the end of the rod 276

is an adjustable nut 281 between which and the collar 277 is interposed a compression spring 282. This spring keeps the rod 276 taut and prevents rattle or disengagement of its left-hand end from the hook 275.

Thus, by turning the hand-wheel 280, conveniently positioned at the right-hand end of the tubular member 57, the arm 275 of the bell crank lever 271 is forced to the left. This movement through the yoke connection 269 moves the slide 255 to the left against the action of the spring 261 to decrease the amplitude of oscillation given to the pouncing tool. The amplitude of oscillation of the pouncing tool may thus conveniently be controlled by hand.

The arm 271^a of the bell crank lever 271 is adapted to contact a roller 283 which is carried in the arm 284 extending substantially at right angles to the arm 271^a. This arm 284, is shown in Figure 15, and is carried upon the pin 54 which connects the connecting arm 48 with the T-lever 53. This arm 284 carries a second roller 285 in position to be acted upon by a cam 286. This cam 286 is adjustably clamped upon the tubular end 52^a of the supporting arm 52 and is tightened and adjusted thereon by means of the clamp screw handle 287, as shown in Figure 15.

The arm 284 being carried by the pin 54 thus partakes of the swinging movement of the T-lever 53 and the member 57 as the tool 65 traverses across the surface of the hat. The roller 285 riding upon the cam 286 swings the lever 284 in a clockwise direction as viewed in Figure 15, and this movement through the roller 283 urges the arm 271^a downwardly as viewed in Figure 14. This causes a movement to the left of the bell crank arm 271 which, through the yoke 269, forces the slide 255 to the left against the action of the spring 261 to decrease the amplitude of reciprocation of the pouncing tool. The face 286^a of the cam 286 has the shape of a segment of a circle, and when the roller 285 is riding on this circular portion, the slide 255 is moved to its extreme left position, thereby centering the rock arm 245 and causing the reciprocations of the pouncing tool to cease.

The cam 286 is so adjusted by means of the clamping screw 287 that the roller 285 rides to the circular portion 286^a just after the pouncing tool 65 reaches the tip of the hat after its traverse across the hat and back again. The pouncing tool will thus remain free from oscillations until it is lifted back again to the tip of the hat at the start of the pouncing operation, as has been described. When this is done the roller 285 leaves the high surface 286^a of the cam 286, permitting the slide 255 to move to the right and permitting the pouncing tool to resume its oscillations.

The arm 284 is bell crank in shape and, as shown in Figure 15, its arm 284^a extends out-

- wardly beneath the tubular member 57 and as will be evident, is swung downwardly when the roller 285 rides up onto the high portion 286^a of the cam 286. Secured to the 5 arm 60, which, as has been described, is mounted loosely upon the tubular member 57 and connects the latter with the tubular member 62, is a projecting arm 288. Pivoted to this arm 288, at 289, is a downwardly extending rod 290 which passes slidably through a lug loosely mounted upon a pin 291 at the end of the arm 284^a. The end of the rod 290 is provided with an adjusting nut 292 above which is a small spiral spring 293.
- 15 When the roller 285 rides upon the high portion 286^a of the cam 286, the arm 284^a slides downwardly along the rod 290 and striking the spring 293 urges the rod 290 downwardly, which, through the arm 288, 20 swings the arm 60 in a clockwise direction as viewed in Figure 15 carrying the tubular member 62 and the pouncing tool 65 away from the hat. When the center of gravity of the tubular member 62 and the pouncing 25 tool swings past the vertical center line of the tubular member 57, they tend to fall further due to gravity and a spring 294 on the rod 290 limits this movement and absorbs the shock.
- 30 The automatic stopping of the tool reciprocations by the cam 286 and the lifting of the pouncing tool away from the hat by the arm 284^a, as just described, preferably occurs just before the worm wheel 36 automatically 35 drops out of engagement with the worm 35 as previously described. The actions of these parts are all subject to adjustment and can be set to occur at the desired time and in the desired order. It will be seen that the 40 entire operation of the machine, including the oval changing mechanism, the velocity changing mechanism, the pouncing tool traversing mechanism and the pouncing tool reciprocating mechanism is automatically 45 started when the pouncing tool is lifted into engagement with the hat and is automatically stopped when the pouncing tool reaches the end of its traversing movement.

With reference again to Figure 14, pivoted 50 upon the same pin 272 which carries the bell crank 271 is a lever 295, the left-hand end of which is adapted to be engaged by a roller 296. This roller, as shown in Figure 15, is carried upon an arm 297 which is pivoted 55 with the arm 284 upon the same pin 54. The arm 297 carries a second roller 298 mounted in an adjustable slide 299 whose position on the arm 297 is determined by a screw 300 adapted to enter holes 301 on the arm 297, as shown 60 in Figure 14. The right-hand end of the arm 295 contacts the end of an adjustment screw 302 threaded into a lug 303 of the bell crank 271. Thus, a movement downwardly, 65 as viewed in Figure 14, of the left-hand end of the lever 295 under the action of the roller

296 swings the bell crank 271 to the left to tend to decrease the amplitude of reciprocations imparted to the tool.

The roller 298 engages a cam 304, which as shown in Figure 14, is secured by screws 305 to a casting 306 which is loosely mounted upon the hollow part 52^a of the supporting arm 52. This casting 306 also supports the outer race of the ball bearing 242 and is provided with a handle 307 by means of which its position upon the part 52^a, and hence the position of the cam 304 may be adjusted. The casting 306 is provided with a rear extension 306^a, as shown in Figure 14^a, in which is a circular segmental slot through which passes 80 a pin 308 extending therefrom through the hollow stud 309 which supports the bearing arm 240 of the tension pulley 239. At the right-hand end of this pin 308 is a compression spring 310 and an adjusting nut 311. The spring 310 urges the pin 308 to the right and this through a suitable friction collar 312, thus urged against the extension 306^a of the casting 306 through the segmental slot in which the pin 308 passes, restrains the handle 90 307 from free movement, but permits convenient adjustment thereof.

The outlines of axial sections of a hat, that is sections taken parallel to an axial line through the tip of the hat, vary greatly in sharpness of curvature, the curvature being much sharper at the portion joining the square of the hat than is the curvature at the remaining portions. The surface of contact between the pouncing tool and the hat therefore varies greatly as the pouncing tool traverses the surface of the hat, the surface of contact being much smaller at the portions of sharper curvature at the square of the hat and hence the intensity of pressure being substantially greater at this portion than at the other portions of the hat. The degree of curvature at the square also varies greatly with different styles and shapes of hats. The cam 304 is designed to automatically decrease the length of reciprocations of the pouncing tool as it passes over the sharp square of the hat, and thus compensate for the increased intensity of pressure at these points to make uniform the amount of work done on all parts of the hat.

In Figure 15, the cam 304 is viewed in end elevation and it is seen that the outline of its acting face at the near end is more pointed and its highest acting surface therefore shorter than is the outline of the acting surface at the far end, where its high portion is fuller and longer. The outline of intermediate portions vary gradually from the contour at the near end to that at the far end. The acting surface of the cam at the near end is designed to take care of hats having the sharpest curvature at the square, while the acting surface at the far end is designed to take care of styles of hats having the most

gradual curvature at the square, the intermediate portions taking care of intermediate styles. The section of the cam which is operative at any time is determined by the adjustment of the slide 299 carrying the roller 295 which coacts with the cam.

The cam 304 is adjusted by means of the handle 307 so that the roller 298 carried by the arm 297 contacts the highest portion thereof at the proper time, which is just as the pouncing tool 65 passes over the sharpest curvature of the square of the hat. When the roller 296 rides up on the cam 304, the lever 295, is viewed in Figure 14, is depressed by the roller 296 which, as above described, through the abutment screw 302, forces the bell crank 271 to the left, decreasing the length of reciprocations given the pouncing tool. The effect of the highest portion of the cam 304 may be regulated by the setting of the abutment screw 302. To aid in the setting of the cam 304 so that the roller 298 will contact the highest portion thereof, at the proper time, a pointer 313 is secured to the adjustable casting 306 cooperating with an index on the frame arm 52.

When the square of the hat being operated upon is very sharp, it may be found desirable to decrease the pressure of the pouncing tool against the hat, as well as to decrease the length of reciprocations of the pouncing tool as it passes over these portions. Referring to Figure 15, the arm 297 is in the shape of a bell crank, the arm 297^a of which extends outwardly beneath the tubular member 57. A rod 314 connected to the arm 288, at 289, with the rod 290, extends downwardly through a lug pivoted at 315 in the end of the arm 297^a. The end of this rod 314 is provided with an adjusting collar 316 and a small spring 317. When the roller 298 rides up on the cam 304, the arm 297^a is swung downwardly and the collar 316 may be adjusted so that the proper engagement with the spring 317 takes place to lift the pouncing tool entirely or decrease its bearing pressure the desired amount.

The oiling of the oscillating mechanism comprising the rocker arm 245 and its controlling parts is accomplished preferably through two oil cups 380 and 381, as shown in Figure 14. Oil from the cup 380 lubricates the ball bearings 243 and 259 and circulating within the cap 263 lubricates the other moving parts therein, any overflow flowing to the left about the sleeve 241 to the ballbearing 243. The oil cup 381 communicates with a passage 383 extending longitudinally through the slide 255. The lubricant passes through holes in the plate 256 to the roller 257 and to the interior of the sleeve 241 which is provided with a groove 384 at its left-hand end into which the oil is thrown by centrifugal force and from which it is led through passages 385 to the ball bearing 243. Oil which works outwardly into the pulley 238 is thrown

through passages 386 and the surplus oil is caught in an oil guard 387 formed in the casting 306. The bottom of this oil guard 387 is provided with openings through which the surplus oil drains into a cup 388, shown in Figure 15. From this cup 388, the surplus oil is led through a pipe 389, shown in Figure 1, toward the rear of the machine and into the gear box 234. The oscillating mechanism is thus dependably lubricated and surplus oil which may work out is disposed of to prevent its being thrown about by the moving parts.

Referring to Figure 14, the connecting rod 267 which, as above described, transmits the oscillations of the oscillating arm 248 to the pouncing tool, is loosely threaded at its end into a collar 318. Threaded also upon the connecting rod 267 are a pair of lock nuts 319 between which and the collar 318 is interposed a compression spring 320. This connection permits the connecting rod 267 to turn slightly at its threaded connections to relieve strain thereon. The collar 318 has a forked end 321 through which loosely passes a pin 322 upon which is loosely mounted a lug 323 which has a hub 324 loosely mounted through a bushing 325 upon a vertical pin 326. This pin 326 through ball bearings, as shown in Figure 2, is supported in an arm 327 which is in turn mounted through ball bearings on a vertical stud 328 carried by the adjustable supporting arm 63. The upper end of the pin 326 forms a bearing 329 which supports a pin 330 connected with the left-hand end of the frame 331 of the pouncing tool. The right-hand end of the frame 331, as shown in Figure 3, has a pin similar to the pin 330 supported in a bearing 332. This bearing 332 is formed on the upper end of a pin similar to the pin 326, the pin being supported in an arm 333 similar to the arm 327 and the arm 333 being mounted upon a pin 334 similar to the pin 328 and supporting the arm 333 upon the adjustable mounting arm 64.

The pouncing tool is thus free to reciprocate, carried by the swinging arms 327 and 333, and driven by the connecting rod 267 from the oscillating arm 248. The pouncing tool is further free to pivot in its bearings 329 and 332 so that its surface may properly align itself to the surface of the hat upon which it is working, and it is found desirable to employ a spring 335 to swing the top side of the pouncing tool over slightly so that it may properly work close to the brim of the hat. Friction washers 332^a of felt or the like interposed between a clamping collar 332^b and the bearing 332, serve to steady the swinging movement of the tool in its bearings.

Turning now to Figure 16, which is a view of the side of the pouncing tool looking upwardly toward the same, relative to its position shown in Figure 1, there is shown an im-

proved and simplified form of mounting of the pouncing tool. At the right-hand side of the pouncing tool, as viewed in this figure, is adjustably secured to the tubular member 62 a collar 336 to which is pivoted by a pin 337 an arm 338. At the left-hand side of the pouncing tool is secured to the tubular member 62 a similar collar 336, not shown, to which is similarly pivoted an arm 339. The ends of the arms 338 and 339 have forked ends 338^a and 339^a which are respectively pivoted to bearings 340 and 341. These bearings 340 and 341 support pins as 342 projecting from the sides of the pouncing tool frame 331. The connecting rod 267 which imparts the reciprocations to the pouncing tool from the oscillating arm 248, is connected to the bearing 340 by a universal joint as a ball and socket connection 343. It will be seen that the pouncing tool is free to reciprocate under the action of the connecting rod 267 being carried by the pivoted supporting arms 338 and 339 and that this mounting is less complicated requiring fewer parts than that previously described.

The pouncing tool comprises a yielding pad having a covering of a suitable pouncing material, such as a suitable grade of sandpaper. The body of the pad preferably comprises a yielding member 344 preferably of felt or similar material secured at its ends, as shown in Figure 18, by clamps 345 and clamping bolts 346. Preferably the pad 344 is supported at its central portion by a coil spring 347 stretched between the clamps 345 at either side.

The sand-paper may be applied to the surface of the pad 344 in any suitable manner, but preferably it is fed across the surface of the pad in a continuous strip during the operation of the pouncing tool. Referring to Figure 18, there is shown a roll 348 supported upon a pin 349, upon which roll the strip of sand-paper 350 is wound after traversing the surface of the pad 344. The supply roll of sand-paper is supported upon a pin 351, shown in Figure 16, and from this roll the strip passes over a guide roller across the surface of the pad 344 and over a guide roller 352 to the receiving roll 348. This receiving roll 348 has a suitable hub 353 projecting through the frame 331, which hub is shaped to coact with a key by means of which the roll may be turned by hand. A spring 354 pressed dog 354 coacting with a ratchet 355 prevents backward rotation of the roll 348. This receiving roll 348 is also driven by automatic means, which will now be described, to maintain a constant feed of the sand-paper strip across the pad surface during operation of the pouncing tool.

Secured between the two side walls 331 of the frame of the pouncing tool is a stationary shaft 356 having a central circular hub 356^a. Freely mounted upon the shaft 356 is a col-

lar 357 which has a part 357^a flanging over the hub 356^a. A sleeve 358 is loosely mounted upon the shaft 356 and has a hub 358^a flanging over the part 357^a of the rotatable collar 357. Secured to the collar 357 is a gear 359 in mesh with a gear 360 which is in turn fixed upon a shaft 361. The shaft 361 carries a worm 362 which meshes with a worm gear 363 carried upon the shaft 349 which supports the sand-paper receiving roll 348. Thus rotation of the collar 357 upon the shaft 356 turns the worm gear 363 and rotates the roll 348.

Resting in a tapered groove 364 in the part 357^a is a spring pressed ball or roller 365 which is adapted to wedge between the part 357^a and the flange 358^a of the rotatable sleeve 358, thus permitting rotation of the sleeve 358 in a clockwise direction, as viewed in Figure 18, to rotate the collar 357, but preventing such drive in the reverse direction. Inserted in a second tapered groove 366 of the part 357^a is a second spring pressed ball 367 which wedges between the part 357^a and the surface of the stationary hub 356^a, thus restraining the collar 357 from rotation in a counter clockwise direction. Thus a rotation back and forth of the sleeve 358 upon the shaft 356, transmits a unidirectional clockwise rotation to the collar 357 and the gear 359, turning the shaft 349 to wind the sand-paper strip upon the roll 348.

Freely mounted upon the outside of the sleeve 358 is the hub 368 of a weighted arm 369. An abutment 370 secured to the rotatable sleeve 358 enters a hole in the arm 369, which hole, as shown in Figure 17, is preferably a little larger than the head of the abutment screw. As the pouncing tool rapidly reciprocates in operating upon the hat, as above described, the weighted arm 369 through inertia oscillates about the shaft 356 between two abutments 371 and 372. This oscillating movement of the arm 369 is imparted to the sleeve 358 and its flange 358^a through engagement and impact with the abutment screw 370 and this, through the friction ball drive just described, drives the sand-paper roll 348 in one direction drawing the sand-paper strip 350 across the surface of the pad 344. The weighted arm 369 is preferably provided with cushions 373 and 374 which strike the abutments 371 and 372 respectively.

The abutment 371 is fixed and the abutment 372 is adjustably mounted through a screw 375 from an arm 376. This arm 376, as shown in Figure 17, is loosely mounted upon the hub 368 and terminates in an arm 377. It will be seen that the amount of feed of the sand-paper strip is governed by the amount of movement of the weighted arm 369 which is in turn governed by the position of the abutment 372. The amount of feed is therefore varied by adjusting the position

of the abutment 372 in its arm 376 and by the position of this arm 376 which is controlled by the position of the arm 377 connected therewith.

5 This arm 377 is adapted to contact the surface of the roll of sand-paper upon the winding roll 348, as shown in Figure 18 and is urged against the same by a spring 378. When the diameter of the roll of sand-paper is small, it is evident that one rotation of the shaft 349 winds a much smaller length of the strip than is wound with one rotation of the shaft 349 when the diameter of the sand-paper roll is larger. As the diameter of 10 the sand-paper roll increases, the arm 377, in contact with the surface thereof, is moved toward full line position, thus moving the abutment 372 nearer the abutment 371 and restricting the amount of oscillation permitted 15 to the weighted arm 369. The rate of rotation of the roll carrying shaft 349 is thus automatically decreased as the diameter of the sand-paper roll increases, and the arm 377 is given the proper curvature to so move the 20 abutment 372 that the sand-paper feed is maintained substantially constant regardless of the size of the winding roll. Thus, as the pouncing tool operates upon the hat a uniform abrasive surface is constantly maintained, making for uniform results and, in 25 addition, the most economical use of the pouncing paper.

Turning back to Figure 7, as has been described, by manipulation of the gear shift handle 189, the gears within the casing 31 may be controlled so that the hat block 34 is driven at either one of two speeds, the faster speed being four times that of the slower speed, due to the ratio of the gearing. In 30 ordinary operation, the hat block is driven at the slower speed, but faster pouncing upon the hat may be accomplished, if desired, by utilizing the faster speed of rotation of the hat. In shifting the gears, the springs 185 and 186 serve not only to reduce strain upon the clutch mechanism, but enable the operator to quickly move the handle 189 to the proper position without waiting for the clutch dogs to mesh, the latter being automatically moved by the springs 185 and 186, 35 and in this manner considerable time on the part of the operator is saved.

It is often found desirable to operate the pouncing tool upon the rotating hat without a reciprocatory movement of the tool in order to lay the fibers of the hat all in one direction. This may be done by arresting the reciprocation of the tool through the hand-wheel 230 (shown in Figure 3) and during 40 such operation upon the hat, the latter may be driven at either the fast speed or slower speed, as is found desirable.

The distance to which the tool traverses toward the brim of the hat is of importance, it being desired that the tool traverse up

5 closely to the brim, but not to a sufficient distance to rub and bind against the brim. This distance may be adjusted by adjusting the swivel clamps 336 (Figure 16) about the tubular member 62 or by adjusting the position of the tubular member 62 (Figure 14) in the clamp supporting arms 60.

Different styles of hats often vary widely in the depth of the crown, that is, in the distance from the brim to the tip. With these extremes in style, it may be found that the traverse movement of the tool requires adjustments in order that the tool may properly traverse the surface of the hat being operated upon. Referring again to Figure 7, 70 there are provided in the connecting arm 48 a plurality of holes, and similar holes are also provided in the crank 44. The connecting arm 47 and the crank 43 at the other side of the machine, are provided with similar holes. The holes in the connecting arm 48 are all at 75 different distances from the center axis of the pin 54 (Figure 15) with which the other end of the arm 48 coacts. The holes in the crank 44 are all at different distances from the center axis of the worm wheel shaft 37. Thus, by changing the bolt connection 48^a between different holes in the connecting arm 48, and the crank 44, different lengths of 80 crank arm, as well as different lengths of the connecting arm 48 to the pin 54, are accomplished. Therefore, for unusually low hats and unusually high hats, as indicated, for example, by the lines 34^b and 34 in Figure 15, the traverse of the tool may be properly adjusted.

From the above it will be seen that there is 85 herein provided apparatus which achieves the various objects of this invention. The machine is capable of operating efficiently and dependably with a minimum of attention by an operator and it is capable of turning out a 90 grade of work of the highest order.

As many possible embodiments may be 95 made of the above invention and as many changes might be made in the embodiment above set forth, it is to be understood that all matter hereinbefore set forth is to be interpreted as illustrative and not in a limiting sense.

110 I claim as my invention:

1. In a machine of the character described, in combination, means adapted to support and rotate a hat, a tool adapted to operate upon said rotating hat, means mounting said tool for manual movement thereof from an inoperative position into an operative position in engagement with the surface of said hat, means adapted to give said tool a traversing movement over the surface of said hat in a predetermined path, and means responsive to movement of said tool adapted when said tool is moved manually from inoperative position into operative position with respect 115

to said hat to render said last means operative.

2. In a machine of the character described, in combination, means adapted to support and rotate a hat, a tool adapted to operate upon said rotating hat, means mounting said tool for manual movement thereof from an inoperative position into an operative position in engagement with the surface of said hat, means adapted to give said tool a traversing movement over the surface of said hat in a predetermined path, and means responsive to movement of said tool adapted when said tool is moved manually from its inoperative position to any point in its path of traverse across said hat to render said last means operative.

3. In a machine of the character described, in combination, means adapted to support and rotate a hat, a tool adapted to operate upon said rotating hat, means mounting said tool for manual movement thereof from an inoperative position into an operative position in engagement with the surface of said hat, means adapted to give said tool a traversing movement over the surface of said hat in a predetermined path, and means responsive to movement of said tool adapted when said tool is moved manually from inoperative position into operative position with respect to said hat to render said last means operative, and means adapted when said tool reaches the end of said path of traverse to move said tool away from said hat and to its said inoperative position.

4. In a machine of the character described, in combination, means adapted to support and rotate a hat, a tool adapted to operate upon said rotating hat, means mounting said tool for manual movement thereof from an inoperative position into an operative position in engagement with the surface of said hat, means adapted to move the axis of rotation of said hat during rotation thereof, and means responsive to movement of said tool adapted when said tool is moved manually from inoperative position into operative position with respect to said hat to render said last means operative.

5. In a machine of the character described, in combination, means adapted to support and rotate a hat, a tool adapted to operate upon said rotating hat, means mounting said tool for manual movement thereof from an inoperative position into an operative position in engagement with the surface of said hat, means adapted to vary the angular velocity of said rotating hat during rotation thereof, and means responsive to movement of said tool adapted when said tool is moved manually from inoperative position into operative position with respect to said hat to render said last means operative.

6. In a machine of the character described, in combination, means adapted to support

and rotate a hat, a tool adapted to operate upon said rotating hat, means mounting said tool for manual movement thereof from an inoperative position into an operative position in engagement with the surface of said hat, means adapted to give said tool a traversing movement over the surface of said hat in a predetermined path, means adapted to move the axis of rotation of said rotating hat during traverse of said tool, and means responsive to movement of said tool adapted when said tool is moved manually from inoperative position into operative position with respect to said hat to render said last two means operative.

7. In a machine of the character described, in combination, means adapted to support and rotate a hat, a tool adapted to operate upon said rotating hat, means mounting said tool for manual movement thereof from an inoperative position into an operative position in engagement with the surface of said hat, means adapted to give said tool a traversing movement across the surface of said hat in a predetermined path, means adapted to vary the angular velocity of said rotating hat during traverse of said tool, and means responsive to movement of said tool adapted when said tool is moved manually from inoperative position into operative position with respect to said hat to render said last two means operative.

8. In a machine of the character described, in combination, means adapted to support and rotate a hat, a tool adapted to operate upon said rotating hat, means mounting said tool for manual movement thereof from an inoperative position into an operative position in engagement with the surface of said hat, means adapted to give said tool a traversing movement across the surface of said hat in a predetermined path, means adapted to reciprocate said tool during said traverse, means adapted to vary the length of said reciprocations during said traverse, and means responsive to movement of said tool adapted when said tool is moved manually from inoperative position into operative position with respect to said hat to render said last means operative.

9. In a machine of the character described, in combination, means adapted to support a hat, a rotatable shaft, means adapted to rotate said hat from said shaft, a tool adapted to operate upon said hat, means adapted to give said tool a traversing movement over the surface of said rotating hat, a detachable driving connection between said shaft and said last means, and means adapted when said tool is moved manually into operative position with respect to said hat, and in response to said movement, to connect said traversing means to be driven by said shaft.

10. In a machine of the character described, in combination, means adapted to

support a hat, a rotatable shaft, means adapted to rotate said hat from said shaft, a tool adapted to operate upon said hat, means adapted to shift the axis of rotation of said hat during rotation thereof, a detachable driving connection between said shaft and said last means, and means adapted when said tool is moved manually into operative position with respect to said hat, and in response to said movement, to connect said shifting means to be driven by said shaft.

11. In a machine of the character described, in combination, means adapted to support a hat, a rotatable shaft, means adapted to rotate said hat from said shaft, a tool adapted to operate upon said hat, means adapted to vary the speed of rotation of said hat during rotation thereof, a detachable driving connection between said shaft and said last means, and means adapted when said tool is moved manually into operative position with respect to said hat, and in response to said movement, to connect said speed varying means to be driven by said shaft.

12. In a machine of the character described, in combination, a rotatable shaft, a worm driven therefrom, means adapted to support and rotate a hat from said shaft, a tool adapted to operate upon said rotating hat, a worm wheel adapted to be driven from said worm and mounted to move into and out of engagement therewith, means connecting said tool to be moved by rotation of said worm wheel, and means coacting with said worm wheel adapted upon rotation thereof by manually moving said tool to urge said worm wheel into driving engagement with said worm.

13. In a machine of the character described, in combination, a rotatable shaft, a worm driven therefrom, means adapted to support and rotate a hat from said shaft, a tool adapted to operate upon said rotating hat, a worm wheel adapted to be driven from said worm and mounted to move into and out of engagement therewith, means connecting said tool to be moved by rotation of said worm wheel, means coacting with said worm wheel adapted upon rotation thereof by manually moving said tool to urge said worm wheel into driving engagement with said worm and means adapted upon movement of said worm wheel into engagement with said worm to move into position to hold said worm wheel in such engagement.

14. In a machine of the character described, in combination, a rotatable shaft, a worm driven therefrom, means adapted to support and rotate a hat from said shaft, a tool adapted to operate upon said rotating hat, a worm wheel adapted to be driven from said worm and mounted to move into and out of engagement therewith, means connecting said tool to be moved by rotation of said worm wheel, means coacting with said

worm wheel adapted upon rotation thereof by manually moving said tool to urge said worm wheel into driving engagement with said worm, means adapted upon movement of said worm wheel into engagement with said worm to move into position to hold said worm wheel in such engagement and means adapted upon predetermined rotation of said worm wheel in engagement with said worm to remove said last means.

15. In a machine of the character described, in combination, a rotatable shaft, a worm driven therefrom, means adapted to support and rotate a hat from said shaft, a tool adapted to operate upon said rotating hat, a worm wheel mounted to move upwardly into engagement with said worm, means connecting said tool to be moved by rotation of said worm wheel, a cam mounted to rotate with said worm wheel and means adapted upon rotation of said worm wheel by manually moving said tool, to be engaged by said cam and raise said worm wheel into engagement with said worm.

16. In a machine of the character described, in combination, a rotatable shaft, a worm driven therefrom, means adapted to support and rotate a hat from said shaft, a tool adapted to operate upon said rotating hat, a worm wheel mounted to move upwardly into engagement with said worm, means connecting said tool to be moved by rotation of said worm wheel, a cam mounted to rotate with said worm wheel, means adapted upon rotation of said worm wheel by manually moving said tool, to be engaged by said cam and raise said worm wheel into engagement with said worm, and means adapted upon predetermined rotation of said worm wheel in engagement with said worm to permit said worm wheel to move downwardly out of engagement with said worm.

17. In a machine of the character described, in combination, a rotatable shaft, a worm driven therefrom, means adapted to support and rotate a hat from said shaft, a tool adapted to operate upon said rotating hat, a worm wheel mounted to move upwardly into engagement with said worm, means connecting said tool to be moved by rotation of said worm wheel, a cam mounted to rotate with said worm wheel, means adapted upon rotation of said worm wheel by manually moving said tool, to be engaged by said cam and raise said worm wheel into engagement with said worm, and means adapted upon movement of said worm wheel into engagement with said worm to move into position to support said worm wheel.

18. In a machine of the character described, in combination, a rotatable shaft, a worm driven therefrom, means adapted to support and rotate a hat from said shaft, a tool adapted to operate upon said rotating hat, a worm wheel mounted to move up-

wardly into engagement with said worm, means connecting said tool to be moved by rotation of said worm wheel, a cam mounted to rotate with said worm wheel, means adapted upon rotation of said worm wheel by manually moving said tool, to be engaged by said cam and raise said worm wheel into engagement with said worm, means adapted upon movement of said worm wheel into engagement with said worm to move into position to support said worm wheel, and means adapted upon predetermined rotation of said worm wheel in engagement with said worm to trip said supporting means.

19. In a machine of the character described, in combination, a rotatable shaft, a worm driven therefrom, means adapted to support and rotate a hat from said shaft, a tool adapted to operate upon said rotating hat, a worm wheel mounted to move upwardly into engagement with said worm, means connecting said tool to be moved by rotation of said worm wheel, a cam mounted to rotate with said worm wheel, means adapted upon rotation of said worm wheel by manually moving said tool, to be engaged by said cam and raise said worm wheel into engagement with said worm, means adapted upon movement of said worm wheel into engagement with said worm to move into position to support said worm wheel, means adapted upon predetermined rotation of said worm wheel in engagement with said worm to trip said supporting means, and means for adjusting the point in the rotation of said worm wheel at which said tripping occurs.

20. In a machine of the character described, in combination, a rotatable shaft, a worm driven therefrom, means adapted to support and rotate a hat from said shaft, a tool adapted to operate upon said rotating hat, a worm wheel mounted to move upwardly into engagement with said worm, means connecting said tool to be moved by rotation of said worm wheel, a cam mounted to rotate with said worm wheel, means substantially counterbalancing the weight of said worm wheel and parts moving therewith, and means adapted upon rotation of said worm wheel by manually moving said tool, to be engaged by said cam and raise said worm wheel into engagement with said worm.

21. In a machine of the character described, in combination, a rotatable shaft, a worm driven therefrom, means adapted to support and rotate a hat from said shaft, a tool adapted to operate upon said rotating hat, a worm wheel mounted to move upwardly into engagement with said worm, means connecting said tool to be moved by rotation of said worm wheel, a cam mounted to rotate with said worm wheel, means adapted upon rotation of said worm wheel by manually moving said tool, to be engaged by said cam and raise said worm wheel into engagement with said

worm, means adapted upon movement of said worm wheel into engagement with said worm to move into position to support said worm wheel, and manual means for removing said action upon said cam and for tripping said supports to permit said worm wheel to drop out of engagement with said worm.

22. In a machine of the character described, in combination, a rotatable shaft, a worm driven therefrom, means adapted to support and rotate a hat from said shaft, a tool adapted to operate upon said hat, a worm wheel mounted to move upwardly into engagement with said worm, means connecting said tool to be moved across the surface of said hat by rotation of said worm wheel, a cam mounted to rotate with said worm wheel, a movable roller adapted to coact with said cam, means urging said roller upwardly toward said cam whereby said roller acting upon said cam raises said worm wheel into engagement with said worm, means controlled by movement of said roller adapted to shift the axis of rotation of said hat during rotation thereof, means controlled by movement of said roller adapted to vary the angular velocity of said hat during rotation thereof, said cam having an undercut portion, and means restraining said roller from moving upwardly into said undercut portion of said cam whereby said worm wheel upon predetermined rotation in engagement with said worm is permitted to drop out of engagement with said worm.

23. In a machine of the character described, in combination, means adapted to support and rotate a hat, means adapted to impart an irregular angular velocity to said hat during rotation thereof and means for varying said irregular angular velocity comprising a sliding plate having angular means slidably engaging said irregular angular velocity means to shift the same.

24. In a machine of the character described, in combination, means adapted to support and rotate a hat, means adapted to impart an irregular angular velocity to said hat during rotation thereof and comprising a linkage having a movable gear, and means comprising a slidably mounted plate having means coacting with said gear and adapted upon movement of said plate to shift the axis of said gear and thereby vary said irregular angular velocity.

25. In a machine of the character described, in combination, means adapted to support and rotate a hat, means adapted to impart an irregular angular velocity to said hat during rotation thereof comprising substantially a linkage having a movable gear adapted upon movement to vary said irregular angular velocity, and means for controlling the position of said gear comprising a slidable plate having an angular slot engaging the axial bearing stud of said gear.

26. In a machine of the character described,

in combination, means adapted to support and rotate a hat, means adapted to impart an irregular angular velocity to said hat during rotation thereof and comprising a linkage having a movable gear, means comprising a 5 slidably mounted plate having means coacting with said gear and adapted upon movement of said plate to shift the axis of said gear and thereby vary said irregular angular velocity, automatic means adapted to move said plate during rotation of said hat, and a spring acting to steady said movement.

27. In a machine of the character described, in combination, a rotatable shaft having a tubular end portion, means connected to said shaft adapted to support a hat and rotate the same therefrom, means adapted to drive said shaft, a longitudinally slidable member in said tubular end portion, a clutch dog resting in a transverse slot in said slidable member and projecting through a transverse slot in said tubular part of said shaft adapted to connect said shaft in driving relation with said driving means, and a member extending longitudinally through said slidable member and engaging said clutch dog to hold the latter in position in said transverse slot.

28. In a machine of the character described, in combination, means adapted to support a hat, means adapted to rotate said supporting means with an eccentric motion, a casing about said last means provided with an enlarged opening through which said supporting means projects, and a cover plate carried by said supporting means slidably engaging the surface of said casing and adapted to cover said opening therein to prevent access of dirt to the interior of said casing.

29. In a machine of the character described, in combination, means adapted to support a hat, means adapted to rotate said supporting means with an eccentric motion, a casing about said last means provided with an enlarged opening through which said supporting means projects, said casing being adapted to contain oil to lubricate said driving means therein, and means adapted to prevent leaking of said oil from said casing outwardly through said opening toward said hat supporting means.

30. In a machine of the character described, in combination with a hat block, a hat block chuck comprising movable gripping members, resilient means urging said members out of gripping position, movable means adapted to act in opposition to said resilient means to urge said gripping members toward gripping position, and means for imparting an impact to said movable means to force said gripping members into gripping engagement with the hat block end to release the same.

31. In a machine of the character de-

scribed, in combination with a hat block, a hat block chuck comprising movable gripping members, a threaded member adapted to force said gripping members into gripping engagement with said hat block, and means for imparting an impact to said threaded member to throw the latter out of gripping position.

32. In a machine of the character described, in combination with a hat block, a hat block chuck comprising movable gripping members, resilient means urging said gripping members out of gripping position, movable means adapted to force said gripping members into gripping engagement with the hat block, and a handle connected to move said last means and permitted movement relative thereto.

33. In a machine of the character described, in combination with a hat block, a hat block chuck comprising pivoted gripping members, a hub on which said gripping members are pivoted, a sleeve threaded on said hub adapted to engage said gripping members and force them into gripping engagement with the hat block, a handle member loosely mounted on said sleeve, and means adapted on predetermined relative rotation of said sleeve and said handle to connect said handle to turn said sleeve on said hub.

34. In a machine of the character described, in combination with a hat block, a hat block chuck comprising pivoted gripping members, a hub on which said gripping members are pivoted, a sleeve threaded on said hub adapted to engage said gripping members and force them into gripping engagement with the hat block, a handle member loosely mounted on said sleeve, means adapted on predetermined relative rotation of said sleeve and said handle to connect said handle to turn said sleeve on said hub, and means restraining said handle member and said sleeve from free relative movement.

35. In a machine of the character described, in combination, a rotatable shaft with a hat block, a hat block chuck connected to rotate therewith, means for operating said chuck to grip and release said hat block, and a manually operated friction brake for holding said shaft against rotation as said chuck is operated.

36. In a machine of the character described, in combination, a rotatable shaft, means connected therewith adapted to support and rotate a hat block therefrom, a reciprocating tool adapted to operate upon a hat supported upon said block, means adapted to impart an irregular angular velocity to said shaft during rotation thereof, and restraining friction means adapted to steady the rotation of said shaft.

37. In a machine of the character described, in combination, a rotatable shaft, means connected therewith adapted to support and rotate a hat block therefrom, a reciprocating

tool adapted to operate upon a hat supported upon said block, means adapted to impart an irregular angular velocity to said shaft during rotation thereof, restraining friction means adapted to steady the rotation of said shaft, and means for adjusting said restraining friction means.

38. In a machine of the character described, in combination, a rotatable shaft, a hat block chuck connected to rotate therewith, means for operating said chuck to grip and release a hat block, a manually operated brake for holding said shaft against rotation as said chuck is operated, means adapted to drive said shaft, a clutch adapted to connect said driving means and said shaft, and means adapted to prevent movement of said clutch into operative position when said brake is operative.

39. In a machine of the character described, in combination, a rotatable shaft, a hat block chuck connected to rotate therewith, means for operating said chuck to grip and release a hat block, a manually operated brake for holding said shaft against rotation as said chuck is operated, means adapted to drive said shaft, a clutch adapted to connect said driving means and said shaft, and means adapted to prevent operation of said brake when said clutch is in operative position.

40. In a machine of the character described, in combination, means adapted to support and rotate a hat, a tool adapted to operate upon said rotating hat, means adapted to cause said tool to traverse the surface of said hat in a predetermined path, weights adapted to effect a pressure of said tool against said hat suspension means for said weights, and a guide for said suspension means adapted to coact therewith substantially to remove the effect of said weights upon said tool as the tool approaches a predetermined point in said traverse.

41. In a machine of the character described, in combination, means adapted to support and rotate a hat, a tool adapted to operate upon said rotating hat, means adapted to cause said tool to traverse the surface of said hat in a predetermined path, suspended weights adapted to effect a pressure of said tool against said hat, and means adapted to prevent swinging of said suspended weights.

42. In a machine of the character described, in combination, a rotatable member, a lever pivoted upon an axis substantially transverse to the axis of rotation of said rotatable member and connected to rotate therewith about said axis of rotation, and means for rocking said lever on its pivot to move the longitudinal axis thereof into and out of line with said axis of rotation.

43. In a mechanism for imparting reciprocating movement, in combination, a rotatable member, a lever pivoted upon an axis substantially transverse to the axis of rotation

of said rotatable member and connected to rotate therewith about said axis of rotation, means tending upon rotation to rock said lever on its pivot to move the longitudinal axis thereof out of line with said axis of rotation, and means limiting said rocking movement.

44. In a machine of the character described, in combination, a rotatable member, a lever pivoted upon an axis substantially transverse to the axis of rotation of said rotatable member and connected to rotate therewith about said axis of rotation, means tending upon rotation to rock said lever on its pivot to move the longitudinal axis thereof out of line with said axis of rotation, means limiting said rocking movement, and means for adjusting said limiting means.

45. In a machine of the character described, in combination, a rotatable member, a lever pivoted upon an axis substantially transverse to the axis of rotation of said rotatable member and connected to rotate therewith about said axis of rotation, said lever being of greater weight on one side of said axis of rotation than on the other side thereof whereby it tends to rock upon its pivot by centrifugal force during rotation, and means limiting said rocking movement.

46. In a machine of the character described, in combination, a rotatable member, a lever pivoted upon an axis substantially transverse to the axis of rotation of said rotatable member and connected to rotate therewith about said axis of rotation, said lever being of greater weight on one side of said axis of rotation than on the other side thereof whereby it tends to rock upon its pivot by centrifugal force during rotation, means for limiting said rocking and means for adjusting said limiting means.

47. In a machine of the character described, in combination, a rotatable member, a lever pivoted upon an axis substantially transverse to the axis of rotation of said rotatable member and connected therewith to rotate therewith about said axis of rotation, means adapted to rock said lever on its pivot to move the longitudinal axis thereof into and out of line with said axis of rotation, means driven from the eccentric rotation of said lever occasioned by the longitudinal axis thereof being out of line with said axis of rotation, and means for controlling the position of said lever on its pivot to control said eccentricity.

48. In a machine of the character described, in combination, a rotatable member, a lever pivoted adjacent its central portion upon an axis substantially transverse to the axis of rotation of said rotatable member and connected to rotate therewith about said axis of rotation, means adapted to rock said lever on its pivot to move the longitudinal axis thereof out of line with said axis of rotation,

means coacting with the portion of said lever on one side of said pivot for controlling the position of said lever upon its pivot, and means driven from the portion of said lever on the opposite side of said pivot.

49. In a machine of the character described, in combination, a tubular rotating member, a lever pivoted upon an axis substantially transverse to the axis of rotation of said tubular member and connected to rotate therewith about said axis of rotation, said lever extending within said tubular member, means tending upon rotation to rock said lever on its pivot to move the longitudinal axis thereof out of line with said axis of rotation, and means within said tubular member adapted to limit said rocking movement.

50. In a machine of the character described, in combination, a tubular rotating member, a lever pivoted upon an axis substantially transverse to the axis of rotation of said tubular member and connected to rotate therewith about said axis of rotation, said lever extending within said tubular member, means tending upon rotation to rock said lever on its pivot to move the longitudinal axis thereof out of line with said axis of rotation, means within said tubular member adapted to limit said rocking movement, and means for controlling said last means.

51. In a machine of the character described, in combination, a tubular rotating member, a lever pivoted upon an axis substantially transverse to the axis of rotation of said tubular member and connected to rotate therewith about said axis of rotation, said lever extending within said tubular member, means tending upon rotation to rock said lever on its pivot to move the longitudinal axis thereof out of line with said axis of rotation, means within said tubular member adapted to limit said rocking movement, resilient means urging said limiting means to maintain said lever in position with its axis in line with said axis of rotation, and means for moving said limiting means against the action of said resilient means.

52. In a machine of the character described, in combination, a tubular rotating member, a lever pivoted upon an axis substantially transverse to the axis of rotation of said tubular member and connected to rotate therewith about said axis of rotation, said lever extending within said tubular member and being of greater weight on one side of said axis of rotation than on the other side thereof whereby it tends to rock upon its pivot by centrifugal force during rotation, means interposed between the wall of said tubular member and said lever adapted to augment said rocking tendency, and adjustable means within said tubular member limiting said rocking movement.

53. In a machine of the character described, in combination, a rotatable tubular member, a lever pivoted upon an axis substantially transverse to the axis of rotation of said tubular member and connected to rotate therewith about said axis of rotation, said lever on one side of said pivot extending within said tubular member and on the other side of said pivot projecting from one end of said tubular member, and said lever being of greater weight on one side of said axis of rotation than on the other side thereof whereby said lever upon rotation tends to rock upon its pivot due to centrifugal force to move into position with its longitudinal axis out of line with said axis of rotation, adjustable means coacting with said inner portion of said lever adapted to limit said rocking movement, and means driven from said outer end of said lever.

54. In a machine of the character described, in combination, a rotatable tubular member, a lever pivoted upon an axis substantially transverse to the axis of rotation of said tubular member and connected to rotate therewith about said axis of rotation, said lever on one side of said pivot extending within said tubular member and on the other side of said pivot projecting from one end of said tubular member, and said lever being of greater weight on one side of said axis of rotation than on the other side thereof whereby said lever upon rotation tends to rock upon its pivot due to centrifugal force to move into position with its longitudinal axis out of line with said axis of rotation, means driven from said portion of said lever projecting from the end of said tubular member, and adjustable means coacting with said portion of said lever within said tubular member and projecting from the other end of said tubular member for limiting said rocking movement.

55. In a machine of the character described, in combination, means adapted to support a hat, a tool adapted to traverse the surface of said hat in a predetermined path and operate thereon, a pivoted lever rotating about an axis extending through said pivot and tending by centrifugal force to move about said pivot into eccentric relation with respect to said axis of rotation, means driven from said lever adapted from the eccentric rotation thereof to transmit a reciprocatory movement to said tool during traverse, means acting in opposition to said centrifugal force upon said rotating lever for controlling the eccentricity thereof, and means adapted automatically to move said controlling means to align said lever with said axis of rotation to discontinue said reciprocatory movement of said tool as said tool reaches the end of said traversing path.

56. In a machine of the character described, in combination, means adapted to support a hat, a tool adapted to traverse the surface of

15 said hat in a predetermined path and operate thereon, a pivoted lever rotating about an axis extending through said pivot and tending by centrifugal force to move about said pivot into eccentric relation with respect to said axis of rotation, means driven from said lever adapted from the eccentric rotation thereof to transmit a reciprocatory movement to said tool during traverse, means acting in 10 opposition to said centrifugal force upon said rotating lever for controlling the eccentricity thereof, and means adapted automatically to move said controlling means to vary the length of the reciprocatory stroke of said tool during said traversing movement thereof.

20 57. In a machine of the character described, in combination, means adapted to support a hat, a tool adapted to traverse the surface of said hat in a predetermined path and operate thereon, a pivoted lever rotating about an axis extending through said pivot and tending by centrifugal force to move about said pivot into eccentric relation with respect to said axis of rotation, means driven from said lever adapted from the eccentric 25 rotation thereof to transmit a reciprocatory movement to said tool during traverse, means acting in opposition to said centrifugal force upon said rotating lever for controlling the eccentricity thereof, means adapted automatically to move said controlling means to vary the length of the reciprocatory stroke of said tool during said traversing movement thereof, and means for adjusting said 30 last means for varying the effect thereof.

35 58. In a machine of the character described, in combination, means adapted to support a hat, a tool adapted to traverse the surface of said hat in a predetermined path and operate thereon, a pivoted lever rotating about an axis extending through said pivot and tending by centrifugal force to move about said pivot into eccentric relation with respect to said axis of rotation, means driven 40 from said lever adapted from the eccentric rotation thereof to transmit a reciprocatory movement to said tool during traverse, means acting in opposition to said centrifugal force upon said rotating lever for controlling the eccentricity thereof, and manual means for moving said controlling means to vary the eccentricity of said lever and the length of the reciprocatory stroke of said tool.

45 59. In a machine of the character described, in combination, means adapted to support a hat, a tool adapted to traverse the surface of said hat in a predetermined path and operate thereon, a pivoted lever rotating about an axis extending through said pivot and tending by centrifugal force to move 50 said pivot into eccentric relation with respect to said axis of rotation, means driven from said lever adapted from the eccentric rotation thereof to transmit a reciprocatory movement to said tool during traverse,

means acting in opposition to said centrifugal force upon said rotating lever for controlling the eccentricity thereof, means adapted automatically to move said controlling means to vary the eccentricity of said lever and the length of the reciprocatory stroke of said tool during said traversing movement thereof, and means adapted automatically to move said controlling means to align said lever with said axis of rotation and discontinue said reciprocatory movement of said tool as said tool reaches the end of said traversing path.

60. In a machine of the character described, in combination, means adapted to support a hat, a tool adapted to traverse the surface of said hat in a predetermined path and operate thereon, means adapted to reciprocate said tool during traverse, a cam, means actuated by said cam adapted to cause said reciprocatory movement of said tool to cease as said tool reaches the end of said traversing path, and means actuated by said cam adapted to move said tool away from said hat as said tool reaches the end of said traversing path.

61. In a machine of the character described, in combination, means adapted to support a hat, a tool adapted to traverse the surface of said hat in a predetermined path and operate thereon, means adapted to reciprocate said tool during traverse, a cam, means actuated by said cam adapted to vary the length of reciprocations of said tool during traverse, and means actuated by said cam adapted to vary the pressure of said tool against said hat during traverse.

62. In a hat pouncing machine, in combination, a reciprocating pouncing pad, an abrasive strip, and means for feeding said strip across said pad including a fixed shaft positioned with its axis transversely of the line of movement of said pad and reciprocating said pad, a weighted member rotatably mounted about said shaft and adapted to oscillate thereon by inertia, means for limiting the oscillating movements of said member, a second member rotatably mounted about said shaft, a plurality of spring pressed balls carried in tapered slots in said second member arranged to rotate said second member in response to movements of said oscillating member in one direction and to coact with said fixed shaft to hold said second member against rotation in response to movements of said oscillating member in the opposite direction, thereby to give said second member an intermittent unidirectional rotation, and means connecting said second member to feed said strip.

63. In a hat pouncing machine, in combination, a reciprocating pouncing pad, an abrasive strip, and means for feeding said strip across said pad including a fixed shaft positioned with its axis transversely of the

line of movement of said pad and reciprocating with said pad, a member rotatably mounted about said shaft, means for giving said member an oscillating movement, a second member rotatably mounted about said shaft, one of said members having an annular portion embracing a part of the other of said members, spring pressed balls carried in tapered slots in said embraced part and arranged to frictionally engage the inner surface of said annular portion and a part of said shaft to transmit to said second member a unidirectional rotation from said oscillating movements of said first member, and means connecting said second member to feed said strip.

64. In a machine of the character described, in combination, a rotatively driven member, a member mounted thereon having an arm adapted to be positioned out of line with the axis of rotation of said first member, said second member and its arm being rotatable with said first member, and means for shifting said second member with respect to said first to vary the position of said arm with respect to said axis of rotation.

65. In a machine of the character described, in combination, a rotatably driven member, a member mounted thereon having an arm adapted to be positioned out of line with the axis of rotation of said first member, said second member and its arm being rotatable with said first member, means for shifting said second member with respect to said first to vary the position of said arm with respect to said axis of rotation, and means for manually operating said last means, said manually operated means being operable during rotation of said members.

66. In a machine of the character described, in combination, a rotatively driven member, a member mounted thereon having an arm adapted to be positioned out of line with the axis of rotation of said first member, said second member and its arm being rotatable with said first member, and means adapted during rotation of said members to shift said second member with respect to said first to vary the position of said arm with respect to said axis of rotation.

67. In a machine of the character described, in combination, a rotatably driven member, a member pivoted upon said first member about an axis substantially transverse to the axis of rotation of said first member, said second member rotating with said first member and having an arm adapted to be positioned out of line with the axis of rotation of said members, and means for swinging said second member about its pivot during rotation of said members to vary the position of said arm with respect to said axis of rotation of said members.

68. In a machine of the character described, in combination, a rotatively driven

member, a member pivoted upon an axis passing transversely through the axis of rotation of said first member and connected by said pivot to rotate with said first member, said second member having an arm adapted to be moved into and out of alinement with the axis of rotation of said members by swinging said second member about its said pivot, means adapted to be driven by said arm and to be given a reciprocating movement thereby, and means for swinging said member about said pivot to vary the length of said reciprocations.

69. In a machine of the character described, in combination, a tubular member mounted to rotate about its longitudinal axis, a member pivoted upon an axis passing transversely through the axis of said tubular member and connected by said pivot to rotate with said tubular member, said pivoted member having an arm projecting from said tubular member and adapted to be moved into and out of alinement with the axis of said tubular member by swinging said pivoted member about its pivot, means adapted to be driven by said arm and to be given a reciprocating movement thereby, and means engaging with said pivoted member at a portion thereof within said tubular member to swing said pivoted member and move said arm to vary the length of said reciprocations.

70. In a machine of the character described, in combination, a tubular member mounted to rotate about its longitudinal axis, a member pivoted upon an axis passing transversely through the axis of said tubular member and connected by said pivot to rotate with said tubular member, said pivoted member having an arm projecting from said tubular member and adapted to be moved into and out of alinement with the axis of said tubular member by swinging said pivoted member about its pivot, means adapted to be driven by said arm and to be given a reciprocating movement thereby, and means including a slidable member within said tubular member for swinging said pivoted member and moving said arm to vary the length of said reciprocations.

71. In a machine of the character described, in combination, a tubular member mounted to rotate about its longitudinal axis, a member pivoted upon an axis passing transversely through the axis of said tubular member and connected by said pivot to rotate with said tubular member, said pivoted member having an arm projecting from said tubular member and adapted to be moved into and out of alinement with the axis of said tubular member by swinging said pivoted member about its pivot, said pivoted member having also an arm extending within said tubular member, and means movable lengthwise of said tubular member having an inclined surface to engage with said last arm

for adjusting the position of said pivoted member about its pivot.

72. In a machine of the character described, in combination, a tubular member mounted to rotate about its longitudinal axis, a member pivoted upon an axis passing transversely through the axis of said tubular member and connected by said pivot to rotate with said tubular member, said pivoted member having an arm projecting from said tubular member and adapted to be moved into and out of alinement with the axis of said tubular member by swinging said pivoted member about its pivot, said pivoted member having also an arm extending within said tubular member, means acting upon said last arm tending to swirl said pivoted member about its pivot and into a position in which said first arm is out of line with the axis of said tubular member, and adjustable means acting upon said inner arm in opposition to said last means for controlling the position of said pivoted member about its pivot.

73. In a machine of the character described, in combination, a tubular member mounted to rotate about its longitudinal axis, a member pivoted upon an axis passing transversely through the axis of said tubular member and connected by said pivot to rotate with said tubular member, said pivoted member having an arm projecting from said tubular member and adapted to be moved into and out of alinement with the axis of said tubular member by swinging said pivoted member about its pivot, said pivoted member having also an arm extending within said tubular member, said last arm being of greater weight on one side of the axis of said tubular member than on the other whereby said pivoted member tends to swing into a position in which said outer arm is out of line with said axis of rotation.

74. In a machine of the character described, in combination, a rotatively driven member having an arm movable into and out of a position in which it is alined with the axis of rotation of said member, means pivotally mounting said arm for rotation with said member and for swinging movement relative to said member about an axis transversely disposed with respect to the axis of said member, means connected to said arm and adapted to be rotated and when rotated to be urged by centrifugal force to swing and to hold said arm out of alinement with said axis of rotation, and means driven by said arm and given a reciprocating movement thereby.

75. In a machine of the character described, in combination, means adapted to support a hat, a tool adapted to traverse the surface of said hat in a predetermined path and operate thereon, a rotatively driven member having an arm movable into and out of a position in which it is alined with the

axis of rotation of said member, means pivotally mounting said arm for rotation with said member and for swinging movement relative to said member about an axis transversely disposed with respect to the axis of said member, means connected to said arm and adapted to be rotated and when rotated to be urged by centrifugal force to swing and to hold said arm out of alinement with said axis of rotation, means driven by said arm adapted to transmit a reciprocating movement to said tool during traverse, and means for determining the position to which said arm may be swung and held.

In testimony whereof, I have signed my name to this specification this 22nd day of March, 1924.

JAMES F. DORAN.

CERTIFICATE OF CORRECTION.

Patent No. 1,771,708.

Granted July 29, 1930, to

JAMES F. DORAN.

It is hereby certified that error appears in the printed specification of the above numbered patent requiring correction as follows: Page 10, line 15, for "top" read tip; page 13, line 14, for "is" first occurrence read as; page 14, line 108, for "272" read 372; page 19, lines 110 and 111, claim 35, for "in combination, a rotatable shaft with a hat block" read in combination with a hat block, a rotatable shaft; page 21, line 52, claim 52, for "sustantly" read substantially; page 22, line 60, claim 59, after "move" insert the word about; and line 109, claim 62, before the word "said" insert the word with; and that the said Letters Patent should be read with these corrections therein that the same may conform to the record of the case in the Patent Office.

Signed and sealed this 28th day of October, A. D. 1930.

(Seal)

M. J. Moore,
Acting Commissioner of Patents.
